ELECTRICAL OUTLET WITH MOVABLE CLOSURE

Philip E. Hamilton, Beaver Falls, Pa.

Application February 28, 1949, Serial No. 78,803

1 Claim. (Cl. 173—330)

1

This invention relates to an electrical outlet with movable closure and more particularly to a safety outlet for the reception of plugs on extension cords.

This application is a continuation-in-part of my co-pending application Serial No. 49,268, entitled "Electrical Outlet," and filed on September 14, 1948.

In the usual electrical outlet, electrical conductors connected with the source of electricity are situated at the base of recesses which are continually open when the outlet is not in use. The recesses are spaced for the reception of the plugs which make contact with the electrical conductors at the base of the recesses. In these conventional fittings, which most often are located slightly above floor level, dirt is free to pass into the recesses. Moreover, it is possible that hairpins and other metallic objects may be inserted in the recesses, for example, by young children and shock the child or cause a short circuit.

In order to overcome the objections to the ordinary outlets, outlets have been designed with a rotating shutter which is normally in a position to close the recesses and prevent the entrance of foreign materials. The safety outlets of this type have heretofore been rather difficult to assemble which adds greatly to their cost of manufacture. Ordinarily, the outlets are made of relatively low cost materials and sold at a low price. Clearly, a complicated structure which is difficult to assemble cannot be commercially successful.

It is increasingly the practice to manufacture electrical appliances with a wire grounding the non-current-carrying metal parts of the appliance and a live wire to the electrical load. Appliances wired in this manner require a positive means preventing inadvertent connection of the ground wire of the appliance to the live wire of the outlets. Obviously, any advantages in safety resulting from the grounding of the appliance are more than overcome if there is a possibility of connecting the ground wire to the hot wire of the outlet.

It is, of course, necessary to construct most parts of the outlet of non-conducting materials. The materials usually employed are various plastic compositions which in most cases have low strength, as compared with metals. It is, therefore, desirable to provide a safety outlet in which the parts thereof are subjected to minimum strains.

It is an object of this invention to provide a safety electrical outlet which closes the recesses

2

in the female electrical connection when the outlet is not in use.

Another object of this invention is to provide an electrical outlet of the safety type which may be easily manufactured and sold at a low price.

It is also an object of this invention to provide a safety electrical receptacle in which the parts are thoroughly insulated and protected to eliminate any possibility of one using the receptacle receiving a shock.

Still another object of this invention is to provide a safety outlet for use with appliances having the non-current-carrying parts grounded, in which connection of the ground wire of the appliance with the live wire of an electrical outlet is prevented.

With these and other objects in view which will become apparent in the detailed description following, this invention resides in an electrical receptacle having electrical conductors in a base member. A shield lies over the conductors having openings in alignment with the conductors and rotatably supporting a shutter having openings normally out of register with the openings in the shield. The shutter and shield each have an opening of one size for reception of a prong of a plug which engages one conductor in the base member and an opening of a different size or shape for the reception of a prong which engages the other conductor. Means limiting the rotation of the shutter are provided allowing the openings in the shutter to move into alignment only with corresponding openings in the shield.

In the drawings:

Figure 1 is a top plan view of the completely assembled electrical outlet comprising this invention;

Figure 2 is a vertical sectional view along section line 2—2 in Figure 1 illustrating the assembled outlet;

Figure 3 is a horizontal sectional view along the section line 3—3 in Figure 2 showing the shield on which the shutter turns;

Figure 4 is also a horizontal sectional view taken along the section line 4—4 in Figure 1 illustrating the position of the conductors in the outlet base of the outlet; and

Figure 5 is an exploded perspective view of the retainer shutter and shield of the outlet described herein.

For purposes of illustration, this invention is described with reference to an outlet having receptacles for plugs from two extension cords. Referring to Figure 2, a wall outlet, indicated

generally by 1, is illustrated as installed in a casing 2, situated in a wall or floor. A bracket 3, attached to the casing 2 by means of screws 4 and to the base member 5 of the outlet by means of screws 6, supports the electrical outlet in the casing. A conventional cover plate 7 is secured over the outlet by means of a screw 8 and completely hides the casing 2.

Referring to Figure 4 of the drawings, the base member 5 consists of a block of insulating material having recesses 9 and 11 for the reception of a grounded conductor 12 and a "live" or "hot" wire connection 13. Recesses 9 and 11 are separated by a rib 14, extending the full length of the base member 5.

Rib 14 of base member 5 has a cavity 15 for the reception of a post in the assembly of the outlet and sockets 16 and 17, which provide bearing spaces for the hub of a shutter employed in this device, in the manner hereinafter described. As is best illustrated in Figure 2 of the drawings, the lower ends of sockets 16 and 17 are grooved as at 18 and 19 for the reception of torsion springs 21 and 22. When the base member 5 is symmetrical it is desirable to drill a hole 23 in the upper surface of rib 14 to insure the proper positioning of the parts during assembly of the outlet.

Conductors 12 and 13 are provided with the usual screws 24 for the attachment of the lead wires to the conductors. Generally, it will be preferable to have the conductors 12 and 13 and their respective screws 24 different colors to facilitate the proper connection of the receptacle when it is installed. In many instances, it will be desirable to mark the outer surface of the base member 5, adjacent conductor 12, with the word "ground."

A flat shield 25 of insulating material having a central opening 26 is placed directly over the base member 5 with the opening 26 in alignment with cavity 15 of the base member. The shield 25 also has holes 27 and 28 drilled therethrough in alignment with the sockets 16 and 17 in the rib 14 of the base member.

Shield 25 is provided with elongated slots 29 extending therethrough to permit the insertion of the prong of a plug of an extension cord into contact with the electrical conductor 12 in the base member 5. Shortened slots 31 also are provided directly opposite the elongated slots 29 and permit contact with the live conductor 13 in the base member 5. The upper surface of the shield 25 is grooved at 32 and 33 by cutting away a portion of the edge of the shield. The grooves 32 and 33 provide positive means preventing contact of the ground wire of the appliance with the conductor 13 in the manner hereinafter described.

The lower surface of the shield member in the outlet illustrated in the drawings is symmetrical and it is possible that the shield could be installed in a reversed position. To insure the proper positioning of the shield during assembly of the outlet, a pin 30, illustrated in Figure 2, is provided on the lower surface of the shield 25. Pin 30 extends into the hole 23 when the shield is properly placed on the base member 5.

Flat, disc-like shutters 34 and 35, also of an insulating material, are placed on the upper surface of the shield 25. Shutter 34 has a hub 36 extending from its lower surface into the hole 27 in the shield 25 and the socket 16 in the base member 5. Hub 36 serves as an axis

about which the shutter rotates. Shutter 35 is similarly equipped with a hub 37, which extends through hole 28 in the shield into the socket 17 in the base member 5. Hubs 36 and 37 are grooved at their lower ends for engagement with the torsion springs 21 and 22, respectively.

An elongated slot 38, having a substantially identical configuration as slot 29, in the shield 25, is provided in shutter 34 and a similar slot 39 is provided in shutter 35. Shutter 34 is also provided with a shortened slot 41, substantially identical in size with slot 31 in the shield 25. A similar slot 42 is provided in the shutter 35.

The shutters 34 and 35 are held in a normal position by the torsion springs 21 and 22 with the slots 38, 39, 41, and 42 substantially perpendicular to, and out of alignment with, the slots 29 and 31 in the shield 25. In this position, a lug 43, extending from the lower surface of the shutter, rides in the groove 32 adjacent the end 44 of the groove 32. Similarly, shutter 35 has a lug 45 adapted to travel in groove 33 and bear against wall 46 at the end of the groove when the shutter 35 is in a normal position. The ends 44 and 46 of the grooves 32 and 33 prevent rotation of the shutters 34 and 35 in a counter-clockwise direction from the normal position illustrated in the exploded view of the device shown in Figure 5. The only possible rotation of the shutters 34 and 35 will bring the elongated slots of the shutters in alignment with the elongated slots of the shields.

Shutters 34 and 35 are held in place on the upper surface of the shield 25 by a retainer 47. This retainer consists essentially of a pair of collars 48 and 49, joined by central bar 51. The collars 48 and 49 fit over the shutters 34 and 35 and allow access to the slots in the shutters. Each of the shutters is provided with a shoulder 52, against which the under surfaces of the collars bear to hold the shutters in place. It is generally desirable to provide legs 53 and 54 at the ends of the collars. These legs fit in grooves 55 and 56 in the shield 25, and 57 and 58 in the base member 5 adding to the rigidity of the outlet.

A post 59 extends downwardly from the center bar 51 of the retainer and passes through opening 26 in the shield 25 into the cavity 15 in the base member 5. Post 59 and cavity 15 are preferably non-circular in cross section and cooperates with legs 53 and 54 to align the parts of the outlet properly. Post 59 is drilled and tapped for the reception of a screw 61, illustrated in Figure 2, which holds the retainer firmly in place against the base member 5 of the outlet. In addition, the cover plate 7, for the outlet is held in place by a screw 62, engaging threads in the post 59.

One of the important advantages of the outlet of the invention is the ease with which it may be assembled. The conductors 12 and 13 are readily slipped into position in the recesses 9 and 11 in the base member. Then torsion springs 21 and 22 are placed in the slots 16 and 17 with their lower ends extending into the grooves 18 and 19 at the bottom of the sockets and the shield 25 is then rested on the base member with pin 30 extending into the hole 23. Shutters 34 and 35 are placed on the upper surface of the shield and held in place by the retainer 47. A rugged unitary structure is provided by screw 61 engaging the base member 5 and the post 59 of the retainer 47. In many instances, it will be desirable that the bracket 3 be attached to the lower surface of the base member 5 as the first step in the assembly.

All of the assembling operations may be easily and quickly performed. The parts slip easily into place and are held in place by gravity during the assembly. Springs 18 and 19 are in their normal uncompressed condition when inserted in sockets 16 and 17, thereby making it unnecessary to work against the force of the spring. After the outlet has been assembled, a finished appearance is provided by the installation of the cover plate 7 by means of the screw 62 engaging the post 59 of the retainer.

The electrical outlet herein described is used with electric appliances having their non-current carrying parts grounded. These appliances are generally equipped with a plug having an enlarged prong for connection with a ground wire, and a small prong for connection with the live wire. The prongs of the plug are inserted in the slots 38 and 41 of shutter 34, the enlarged prong for connection with the ground being inserted in slot 38. Shutter 34 is rotated to bring the slots into alignment with the slots in the shield 25, directly below the shutter and the prongs of the plug are pushed through the slots in the shield into contact with the conductors 12 and 13.

The electrical outlet of this invention provides positive means for preventing accidental contact of a prong on a plug on an extension cord with the wrong electrical conductor. Since the shutter may move in only one direction, it is not possible to align the shortened slot 41 in the shutter 34 with the elongated slot 29 in the shield 25. Similarly, the enlarged prong of a plug cannot be inserted in the elongated slot 29 of the shutter and then brought into alignment with the shortened slot 31 in the shield 25. In this manner, danger of the grounded parts of the appliance being connected with the live wire in the receptacle is eliminated.

While this invention has been described in detail with respect to a particular modification of

the invention, it is to be understood that the concept of this invention is not limited to those details, but is determined by the scope of the appended claim.

5 I claim:

An electrical outlet comprising a base member having a grounded conductor and a live conductor therein, a non-circular cavity in the base, a shield on the base covering the conductors and having a hole in register with the cavity in the base, a large slot in the shield in register with the grounded conductor, a small slot in the shield in register with the live conductor, a shutter pivotally mounted on the shield, said shutter having a large slot and a small slot therein, the slots in the shutter normally being out of register with the slots in the shield, a groove in the surface of the shield, a lug extending from the shutter into the groove, said lug and groove permitting rotation of the shutter only in a direction to align the large and small slots in the shutter with the large and small slots in the shield respectively, a retainer over the shutter holding the shutter against the shield, a post extending from the retainer into the cavity, and a screw engaging the post and the base to form a unitary structure.
